UNITED STATES PATENT OFFICE.

SIDNEY C. WOOD, OF BROOKLYN, NEW YORK.

DESIGN FOR A FOUNTAIN SYRINGE BAG.

Application filed April 22, 1926. Serial No. 17,390. Term of patent 14 years.

To all whom it may concern:

Be it known that I, SIDNEY C. WOOD, a citizen of the United States, residing in Brooklyn, in the county of Kings and State of New York, have invented a certain new, original, and ornamental Design for Fountain Syringe Bags, of which the following is a specification, reference being had to the accompanying drawing, forming a part thereof, and of which Figure 1 is a side elevation and Fig. 2 is a plan view of a fountain syringe bag showing my new design.

I claim:

The ornamental design for a fountain syringe bag as shown.

SIDNEY C. WOOD.
